UNITED STATES PATENT OFFICE.

CHARLES D. WHITE, OF EAST ORANGE, NEW JERSEY, ASSIGNOR TO BRANDES LABORATORIES, INC., OF NEWARK, NEW JERSEY, A CORPORATION OF NEW JERSEY.

ELECTROMAGNETIC SOUND REPRODUCER.

Application filed July 15, 1926. Serial No. 122,636.

My invention relates broadly to electromagnetic sound reproducers and more particularly to an electromagnetic sound reproducer of the cone diaphragm type.

5 One of the objects of my invention is to provide a construction of cone speaker which is capable of reproducing radio broadcast signaling energy at large volume and with pleasing tone quality.

10 Another object of my invention is to provide a simplified construction of cone speaker having a direct acting conical diaphragm actuated by an electromagnetic driver in which a sound amplifying chamber is provided at the rear of the conical diaphragm for the reproduction of notes over the entire musical scale without distortion.

15 Another object of my invention is to provide an inexpensive construction of cone speaker wherein the reproduction of sound from the conical diaphragm depends upon the amplification of the sound by a sound amplifying chamber in which the diaphragm is housed with means for accurately adjusting the magnetic gap between the pole tips of the electromagnetic driving mechanism and the armature from which connection is made to the reproducing conical diaphragm.

20 Another object of my invention is to provide a construction of cone speakers in which a bowl shaped sound amplifying chamber is provided directly adjacent the conical sound reproducing diaphragm, the bowl shaped sound amplifying chamber enclosing an area substantially larger than the area enclosed by the conical shaped diaphragm whereby musical notes reproduced by the operation of said diaphragm are amplified by the sound reproducing chamber.

25 Still another object of my invention is to provide an inexpensive construction of cone speaker in which a single casting forms the sole means of support for a sound amplifying chamber, and an electromagnetic driving mechanism centrally positioned within the chamber to which a conical shaped diaphragm is connected and to which sound vibrations are imparted by the electromagnetic driving mechanism.

30 Other and further objects of my invention reside in the construction and arrangement of parts in the electromagnetic sound reproducer by which the manufacture and production of cone speakers may be facilitated, as will be more fully described in the following

specification by reference to the accompanying drawings in which:

Figure 1 is a vertical cross-sectional view taken through the cone speaker of my invention illustrating the electromagnetic operating mechanism in side elevation; Fig. 2 is a view looking toward the rear of the electromagnetic driving mechanism within the cone speaker on line 2-2 of Fig. 1; Fig. 3 is a detailed cross-sectional view of the electromagnetic driving mechanism and adjustable control mechanism therefor; Fig. 4 is a front view of the electromagnetic driving mechanism showing the means which are provided for supporting the sound reproducing diaphragm from the housing of the electromagnetic operating mechanism; and Fig. 5 is a cross-sectional view taken through the electromagnetic driving mechanism on line 5-5 of Fig. 4.

35 My invention is directed to that class of cone speakers depending for their operation upon a sound amplifying chamber in which the conical sound reproducing diaphragm is housed in accordance with the principles set forth in copending application for Letters Patent, Serial Number 60,128, filed October 2, 1925 by Cyril A. Brigham and David H. Moss. I provide, however, a construction 40 of cone speaker which is considerably simplified over the constructions heretofore employed and the expense in manufacture and production considerably reduced. The embodiment of my invention, however, has proved highly satisfactory in operation by 45 reason of the cooperation of the bowl shaped sound amplifying chamber with the conical shaped sound reproducing diaphragm for 50 efficiently reproducing musical notes over the entire musical scale.

55 Referring to the drawings in more detail reference character 1 designates a casting which forms the base for the cone speaker of my invention. The casting has a vertically extending portion 2 bent at an angle 60 as indicated at 3 with a substantially circular portion 4 at its upper extremity for housing the electromagnetic operating mechanism. The casting is provided with lug members 5, 6 and 7 extending from the sides thereof 65 and cast integral therewith. These lug members serve as attachment means for the angularly shaped arms 8, 9 and 10 on the extremities of which a retaining rim 11 is 70 clamped within which the conical shaped 75

sound reproducing diaphragm 12 is arranged to float. The conical shaped sound reproducing diaphragm 12 is flexibly connected to the rim 11 by means of the annular strip 5 represented at 14 which is attached to the peripheral edge of the cone shaped sound reproducing diaphragm at 15. The strip members 8, 9 and 10 are so shaped as represented at 16 that they clear the peripheral 10 edge 15 of the sound reproducing diaphragm and the movement of the annular rim member 14 so that the conical shaped diaphragm 12 is free to vibrate without restriction. The apex of the conical shaped diaphragm 12 has a connecting member 17 connecting thereto through a screw collet chuck mechanism 18 whereby mechanical vibrations from the electro-magnetic driving mechanism which is housed within the circular 15 casting 4 may be imparted to the sound reproducing diaphragm 12.

The circular casting 4 is apertured as represented at 19 with annular abutment 20 formed therearound against which an armature member 21 is seated and locked in position by means of the locking ring 22 screw threaded in the internal screw threads 23 formed in the circular housing 4. An electromagnetic operating mechanism is supported from a screw threaded plate 24 which may be adjusted in the internal screw threads 23 for advancing or retracting the electromagnets 25 with respect to the armature 21 for selecting a proper magnetic gap 30 for the reproduction of signaling energy of a particular characteristic. The electromagnetic operating mechanism includes the electromagnets 25, pole pieces 26 and permanent magnets 27 mounted from the plate 24. A spring 28 is arranged between the plate 24 and the locking ring 22 for preventing undesired noises from the mechanical parts of the driver during operation of the apparatus.

I prefer to employ a construction of armature 21 as described more particularly in Letters Patent No. 1,588,545 granted to William H. Gerns, June 15, 1926. The armature may be mounted in a variety of ways, particularly as set forth in Letters Patent 1,526,626 dated February 17, 1925 granted to Cecil E. Brigham.

Leads are brought out from the electromagnetic driving mechanism as represented at the terminals 29 and flexible connections 30 extend therefrom passing to the exterior of the apparatus. The housing which is formed around the conical shaped diaphragm comprises a bowl shaped member 31 having an annular flange 32 around its periphery cut away adjacent the base 1 as represented at 33 to form a bracket for the support of the bowl shaped member from the base 1 by any suitable means, such as securing screws 34. The bowl shaped am-

plifying chamber is braced adjacent its top 36 by means of a bracket member 35 terminating at 37 on the lug 5. The front of the sound amplifying chamber is closed by means of an annular face plate 38 suitably ornamented for improving the esthetic appearance of the speaker. The face plate 38 is centrally apertured as represented at 39 and is provided with an annular flange 40 with a beaded edge 41 which fits over the raw edge of the annular flange 32 of the bowl shaped back 31 with an annular gasket 42 therebetween. This gasket 42 may be of cork or resilient material to prevent inherent metallic noises on large volumes. The face plate 38 is supported with respect to the bowl shaped back 31 by means of screw devices 43 which pass through the flanges 40, 32 and gasket 42 at a plurality of points around the periphery of the bowl shaped amplifying chamber 31. In order to adjust the position of the electromagnetic operating mechanism with respect to the driving armature a pinion 44 is keyed to a shaft member 45 which is journaled in the lug member 5 and secured therein by means of a spring device 46 which engages the cut away portion 47 of the operating shaft 45 in the manner of a yoke. The pinion 44 meshes with teeth 48 formed on the annular rim of the plate 24 whereby rotation of pinion 44 serves to move the electromagnetic operating mechanism to a selected position with respect to the armature 21. The locking ring 22 may be adjusted to permit the assembly and adjustment of the armature member 21 in that position for maximum operating efficiency. In order to prevent abutment of the pole pieces 26 against the armature 21 I provide a limiting stop device 49 which extends radially from the center of the rotatable plate 24 and limits the movement of the electromagnetic operating mechanism in the direction of the armature 21 by reason of obstruction formed by the operating shaft 25 in the path of the member 49. A complete turn of the electromagnetic operating mechanism is therefore limited by the engagement of member 49 with opposite sides of operating shaft 45. The flexible conducting cord 30 is looped through an aperture in the limiting stop 49 for preventing entanglement of the conductors with parts of the loud speaking mechanism. The operating shaft 45 passes out of the sound amplifying chamber through a bushing 50 provided in the wall of the bowl shaped back 31 and terminates in a control knob 51 by which the electromagnetic operating mechanism may be rotated for securing the desired adjustment.

It will be observed that the construction of the cone speaker lends itself to quantity production and manufacture by reason of

the pressed metal parts and the casting from which the parts are mounted. I have found the construction as illustrated extremely practical, although I desire it to be understood that modifications may be made within the scope of the appended claims without departing from the spirit of my invention.

What I claim and desire to secure by Letters Patent of the United States is as follows:

1. An electromagnetic sound reproducer comprising a support, an electromagnetic driver mounted on said support, a conical shaped sound reproducing diaphragm arranged to be actuated by said electromagnetic driver and a bowl shaped sound amplifying chamber surrounding said conical shaped diaphragm whereby said diaphragm operates in substantially confined air within said sound amplifying chamber for the reproduction of musical notes over a broad range of frequencies.
2. An electromagnetic sound reproducer comprising in combination a casting forming a supporting member, an electromagnetic driving mechanism carried by said casting, a conical shaped sound reproducing diaphragm actuated by said electromagnetic driving mechanism and a bowl shaped sound amplifying chamber carried by said supporting member adjacent said conical shaped sound reproducing diaphragm for the amplification of sound delivered by said diaphragm.
3. An electromagnetic sound reproducing apparatus comprising a supporting base having a vertically extending integral member, a circular housing carried by the extremity of said vertically extending member, an electromagnetic driving mechanism supported within said circular housing, a conical shaped sound reproducing diaphragm, and a sound amplifying chamber supported from said vertically extending integral member enclosing said electromagnetic operating mechanism and one side of said conical shaped sound reproducing diaphragm whereby sound delivered by said conical shaped sound reproducing diaphragm is amplified by said chamber.
4. An electromagnetic sound reproducing apparatus comprising a base member having a vertical extension thereon, an electromagnetic operating mechanism carried by the extremity of said vertical extension, a conical shaped sound reproducing diaphragm actuated by said electromagnetic operating mechanism, and a bowl shaped sound amplifying chamber supported from said vertical extension and surrounding said conical shaped sound reproducing diaphragm for amplifying sound delivered by said diaphragm.
5. An electromagnetic sound reproducer comprising a supporting base having a sub-

stantially vertical extension therefrom, a circular housing carried on the extremity of said vertical extension, an electromagnetic driving mechanism supported within said housing, said driving mechanism including an armature and an electromagnetic operating mechanism, a conical shaped sound reproducing diaphragm, a connection between the apex of said conical shaped diaphragm and said armature, a sound amplifying chamber supported from said base and means extending exteriorly of said sound amplifying chamber for adjusting the position of said electromagnetic operating mechanism with respect to said armature whereby sound delivered by said conical shaped sound reproducing diaphragm may be substantially amplified by said sound amplifying chamber.

6. An electromagnet sound reproducer comprising a base member, a vertical member extending from said base member, an electromagnetic driving mechanism carried by said vertical member, a conical shaped sound reproducing diaphragm connected to said electromagnetic driving mechanism and a pair of closure members fitting on opposite sides of said vertical member and forming a sound amplifying chamber around said conical shaped sound reproducing diaphragm whereby the sound delivered by said diaphragm is amplified.

7. An electromagnetic sound reproducer comprising a base member, a vertical member extending from said base member, an electromagnetic driving mechanism carried by said vertical member, a conical shaped sound reproducing diaphragm actuated by said electromagnetic driving mechanism, a bowl shaped closure member supported from said base member adjacent one side of said conical shaped sound reproducing diaphragm and an annular plate encircling the opposite side of said conical shaped sound reproducing diaphragm and supported from the peripheral edge of said aforementioned bowl shaped closure and forming a sound amplifying chamber around said conical shaped sound reproducing diaphragm whereby sound delivered by said diaphragm is increased in amplitude.

8. An electromagnetic sound reproducer comprising a base member, a vertical member extending from said base member, an electromagnetic driving mechanism carried by said vertical member, a conical shaped sound reproducing diaphragm actuated by said electromagnetic driving mechanism, a bowl shaped closure member supported by said base member adjacent one side of said conical shaped sound reproducing diaphragm and an annular face plate secured to the peripheral edge of said bowl shaped closure member through which said conical shaped sound reproducing diaphragm is arranged.

4 to project whereby a sound amplifying chamber is formed around said conical shaped sound reproducing diaphragm for the amplification of sound delivered by 5 said conical shaped sound reproducing diaphragm.

9. An electromagnetic sound reproducer comprising a base member, a vertical extension on said base member, an electromagnetic 10 driving mechanism carried by said vertical extension, a conical shaped sound reproducing diaphragm actuated by said electromagnetic driving mechanism and a sound amplifying chamber comprising a pair of sections 15 telescopically fitting around said conical shaped sound reproducing diaphragm with said conical shaped sound reproducing diaphragm projecting through one of said sections for the amplification of sound delivered by 20 said conical shaped sound reproducing diaphragm.

10. An electromagnetic sound reproducer comprising a base member, a vertical extension on said base member, an electromagnetic 25 driving mechanism carried by said vertical extension, a conical shaped sound reproducing diaphragm actuated by said electromagnetic driving mechanism and a sound amplifying chamber comprising a pair of circular

closure members each having a diameter substantially larger than the diameter of said conical shaped sound reproducing diaphragm with said conical shaped sound reproducing diaphragm projecting through one of said closure members, said closure 30 members being secured together at their peripheral edges for forming a sound amplifying chamber around said conical shaped sound reproducing diaphragm for the amplification of sound delivered by 35 said conical shaped sound reproducing diaphragm.

11. An electromagnetic sound reproducer comprising a base member, a vertical member extending from said base member, an electromagnetic driving mechanism carried by said 40 vertical member, a conical shaped sound reproducing diaphragm actuated by said electromagnetic driving mechanism and a sound amplifying chamber supported from said base member, said sound amplifying chamber having a diameter larger than the largest diameter of said conical shaped sound reproducing diaphragm whereby sound delivered by 45 said sound reproducing diaphragm is amplified by said chamber.

55 In testimony whereof I affix my signature.

CHARLES D. WHITE.
